MAIL LOADING AND UNLOADING CRANE

Application filed June 17, 1929. Serial No. 371,653.

This invention relates to means for transferring mail to and from trains to mail bag mechanism located on station platforms and the like. An essential object of the invention is the provision of an improved mechanism for transferring mail to and from moving trains without damaging mail sacks in any respect.

In the drawing:

10 Figure 1 is an elevation illustrating the application of the invention to a track-side post and the side of a mail car.

Figure 2 is a similar elevation illustrating the mechanism as mounted on a mail car.

15 Figure 3 is a top plan view of the track-side mechanism.

Figure 4 is a top plan view of the car mounted mechanism.

20 Figure 5 is a fragmentary elevation of an element employed on the crane structure.

Figures 6, 7, and 8 are elevations of structural details forming a part of the mechanism.

25 The invention broadly comprises a pair of mail cranes one of which is located on a track-side post and the other of which is mounted at the side of a mail car door, the cranes being substantially of counter-part construction and arranged in oppositely mounted position. In detail the invention as illustrated comprises a track-side post 18 which has secured thereto in vertically spaced relation a pair of lateral brackets 8 anchored to the post by means of the bolts 21. These 30 brackets provide vertical bearings for a vertically disposed shaft 9 bent laterally at its lower end to form a crane arm which extends in the direction of the track.

35 At its upper end the shaft 9 carries a pinion 5 which is in mesh with a similar beveled pinion 5 carried by the shaft 6 of a hand wheel 1 which is journaled transversely through the post 18, bearing plates 4 serving to hold the shaft 6 in position and being anchored by means of the tie bolts 3 passed transversely through the bearing plates and post. A spring finger 2 having one end anchored to the post 18 is adapted for frictional engagement with the hub of the hand wheel 1 and this spring finger serves not

only to hold the crane in adjusted position by reason of its frictional bearing, but acts also as an indicator by which the position of the crane may be regulated.

Above the upper bracket 8 the shaft 9 has rigidly secured thereto a perpendicular arm 7 provided on its side face with a cushion element 10 and having secured to its outer end a cross bar 11 adapted to extend parallel to a trackway and at the outer end of which are upstanding pins 12.

At the bottom of the shaft 9 the crane arm formed by the lateral extension of the shaft carries a spring clip member 16 in which is loosely positioned a ring member 17 having a link 13 supporting the same in depending relation from the tip of the crane arm, said link 13 being held in engagement with the tip of the crane arm by the vertical frictional bearing of a spring clip 14.

On the car door frame 19 a second pair of vertically spaced brackets 8 is mounted and these brackets form vertical bearings for the vertical shaft 23 which is identical in construction with the shaft 9 except that in this instance the crane arm portion of shaft 23 is extended from the upper end thereof having a spring clip 14 which serves to hold the link 13 loosely on the crane arm and maintain in suspended relation the ring member 17 which is engaged by a spring clip 15 rigidly secured to the shaft 23.

At its lower end the shaft 23 has operative connection through the beveled pinions 5 with the shaft 6 of the hand wheel 1 journaled through the door frame and having a structural disposition and mounting which is identical with respect to details to the hand wheel 1 previously described as mounted on the track-side post 18.

Extending from the lower end of the shaft 23 is a perpendicular arm 7 having a cushion 10 and carrying at its outer end a cross arm 11 provided adjacent each end with upstanding pins 12.

In the proper disposition of the elements as indicated in Figures 1 and 2 the cross arms 11 are disposed in parallel vertically spaced relation and occupy a common vertical plane. In practice a mail bag, not shown, is suspend-

ed from the upper ring element 17 and a second mail bag, not shown, is suspended from the track-side ring 17. As the train approaches the track-side element the upper ring 17 will be caught and held suspended from the track-side mounted arm 7 while at the same time the ring 17 carried by the track-side crane will be caught and held suspended over the arm 7 of the main car crane, thus effecting a simultaneous transfer of the suspended mail bags.

While in this embodiment we have illustrated and described certain structural details entering into the construction and operation, we desire it to be understood that such details do not constitute limitations, but that any desired changes and modifications may be made therein as will fall within the scope of the invention as claimed.

20 We claim:

1. Mail transfer mechanism comprising in combination, a track-side crane, a car carried crane, said cranes being reversed with respect to one another, means for suspending a mail bag by one end from each of said cranes, means on each of said cranes for engaging the suspended mail bag carried by the other crane in a simultaneous transfer, and manually operable means for moving said cranes into mail bag transfer position.

2. A mail bag transfer comprising in combination a track-side post, a crane supported by said post to swing across a track, said crane having a vertically arranged shank and a laterally extending hook portion on its lower end, a grab arm secured to said shank at its opposite end in parallel spaced relation with respect to said hook portion, a train carried crane of counterpart formation with respect to said track-side crane and arranged in reverse relation with respect thereto to dispose its hooked end portion above the grab arm of the track-side crane, and means for suspending mail bags from the hooked end portions of said cranes.
